UNITED STATES PATENT OFFICE.

EMIL BOMMER, OF BROOKLYN, NEW YORK.

SPRING-HINGE.

1,241,085.

Specification of Letters Patent. Patented Sept. 25, 1917.

Application filed May 29, 1917. Serial No. 171,632.

To all whom it may concern:

Be it known that I, EMIL BOMMER, a citizen of the United States, and a resident of the borough of Brooklyn, county of Kings, city and State of New York, have invented certain new and useful Improvements in Spring-Hinges, of which the following is a full and complete specification.

My invention relates to spring-hinges for doors or other swinging structures, and has for its object to provide a strong and readily manufactured device of this class which will permit of throwing the spring out of action when desired, so that, at the user's choice, the door or other swinging member will either remain in any position to which it may be placed, or return to a definite normal position.

The invention will now be described in detail, and its novel features will then be pointed out in the appended claims.

Two typical embodiments of my present invention are illustrated by the accompanying drawings, in which—

Figure 1 is a front elevation of a door provided with one form of my improved spring-hinge;

Figs. 2, 3 and 4 are sections taken on lines 2—2, 3—3, and 4—4 respectively of Fig. 1;

Fig. 5 is a detail perspective view of a connecting and stop member employed in this form of my invention;

Fig. 6 is a front elevation of a door provided with another form of spring-hinge constructed according to my invention;

Figs. 7, 8 and 9 are sections taken on lines 7—7, 8—8, and 9—9 respectively of Fig. 6; and

Fig. 10 is a perspective view of the connecting and stop member used in this second form of my invention.

The door or other swinging member 20 is provided at the hinge corner with the following parts, which are connected with the door rigidly and form a casing for the hinge-spring and the release mechanism.

Two spaced vertical members or plates 21, 22 located adjacent to each other, on one side of the spring 23, another vertical bar or member 24 located on the other side of said spring, and two horizontal or transverse connecting members 25, 26 located at the top and bottom respectively, provided with alining apertures for the reception of a stationary vertical axle 27 resting in a support 27'. To this axle is secured rigidly a

collar 28, and loosely the two end portions or collars 29', which with the longitudinal bar 29 extending at one side of the spring 23, form a connecting and stop member for the purpose set forth below. Longitudinal movement of this member is prevented, according to Figs. 1 to 5, by fitting it between the lower face of the transverse member 25 and the upper face of the collar 28, while according to Figs. 6 to 10, the upper and lower collars 29' engage respectively the lower surface of the transverse member 25 and the upper surface of the transverse member 26. On the axle 27 are also mounted loosely two rings or collars 30, 30', to which the respective ends of the coiled spring 23 are secured. The upper collar 30 has a rigid pin 31 projecting beyond the bar 29 and adapted to engage it at one side, while the lower collar 30' has a similar pin 31' adapted to engage the bar 29 on the opposite side (see Figs. 3, 4, 8 and 9). It will be understood that the torsional tension of the spring 23 tends to bring the pins 31, 31' against opposite sides or edges of the bar 29 as shown best in Fig. 3. Preferably one of the pins 31, 31' (say the lower pin 31') may be connected with its collar at different points, to permit of adjusting the stiffness and torsional tension of the spring 23. Thus, as shown in Figs. 4 and 9, the collar 30' has a plurality of radial sockets 30'', any one of which may receive the pin 31'. The outer ends of the pins 31, 31' are also adapted to engage suitable abutments on the door; in Figs. 1 to 5 these abutments are formed on the vertical member 22, as indicated at 32, 33; in Figs. 6 to 10 they are formed by the opposite edges of the longitudinal member 24.

In each of the constructions shown, the connecting and stop member 29, 29' is normally stationary, by locking to the collar 28, the adjacent end portion of said member, and means are provided for releasing said member, so that it may move freely with the door when desired.

In Figs. 1 to 5, the locking and releasing means are constructed as follows: The lower end portion or collar 29' is provided with a longitudinal socket 29'' (which may also extend upwardly along a portion of the bar 29), and into this socket is adapted to be projected upwardly a coupling pin 34 mounted to slide vertically in a socket of the stationary collar 28 and pressed by a coiled spring 35. As shown in Figs. 1 and

4, the pin 34 in its normal locking position projects from the socket 29'', and this projecting portion is adapted to register (when the door is in the closed position shown) 5 with a projection 36 on a vertically sliding releasing plunger 37, suitably guided between the plates 21, 22 and pressed upward by a spring 38. The plunger may be depressed by means of cam levers 39 ful- 10 crumed at 40 to swing about a horizontal axis, and arranged between the plates or bars 21, 22. The drawings show two levers of this character, projecting to opposite sides of the door, but in practice one of these 15 levers may be omitted if desired.

In the construction illustrated by Figs. 6 to 10, the socket 29 for receiving the coupling pin 34 is made at the edge of the upper collar or end portion 29' and is adapted 20 to be depressed out of engagement with said socket, by the projection 36' of the vertically-sliding plunger 37' pressed upward by a spring 38' and forward by a spring 38''. The cam levers 39' (one of which may be 25 omitted) are fulcrumed at 40' and serve to depress the plunger when desired. The door frame is indicated at 41.

The operation of the construction shown in Figs. 1 to 5 is as follows: The coiled 30 spring 23, acting on the pins 31, 31' through the collars 30, 30', keeps said pins against the opposite edges of the bar 29, and as the latter is normally stationary (being locked to the collar 28 by the coupling pin 34), it 35 follows that the pins 31, 31' by their engagement with the abutments 32, 33 on the door 20 will tend to keep the latter in the closed or normal position illustrated. Let us assume that the door is now swung in such a 40 direction as to turn the pin 31 clockwise from the position shown in Fig. 3. The upper collar 30 will move in unison with said pin and place the spring 23 under torsional tension, since the lower end of the spring 45 cannot follow this clockwise movement, the pin 31' connected with such lower end, being in engagement with the stationary bar 29 (Fig. 4). Therefore, as soon as the door is released, the spring 23 will swing it back 50 to the normal position shown. Should the door be swung in the opposite direction (contra-clockwise in Figs. 3 and 4), the projection or abutment 33 will act on the pin 31' and through the collar 30' on the lower 55 end of the spring 23, the upper end of the spring being prevented from following this movement owing to the engagement of the pin 31 with the stationary bar 29. The spring 23 will thus be put under torsional 60 tension, so as to return the door to its normal position.

Now let us assume that (with the door in the normal position) the plunger 37 is depressed so as to remove the coupling pin 34 65 from engagement with the member 29, 29'.

If then the door is swung, say clockwise, the pin 31 and the upper end of the spring 23 will move as before, but the lower end of the spring, instead of remaining stationary, will move in the same direction, since the bar 29 70 is now free to move about the axle 27 as a center. The door therefore can move to any desired position, without putting the spring 23 under torsional tension, and the door will stay in whatever position it may be placed. 75 If the door is swung back to its normal, closed position, the spring 35 will cause the pin 34 to snap back to its normal, coupling position.

The construction shown in Figs. 6 to 10 80 will operate in the same manner as the one illustrated by Figs. 1 to 5. The pins 31, 31' and the bar 29 are arranged adjacent to the bar 24, instead of being on the side of the bar 22, and the stationary collar 28 is above 85 the spring 23 instead of below the same, but in principle the operation is the same, so that repetition of the explanation given is thought unnecessary.

Suitable cover plates (not shown) may be 90 employed, if desired, to protect and incase the spring 23 and other parts.

While I have shown two preferred and satisfactory forms of my invention, it is obvious that changes may be made therein, 95 within the spirit and scope thereof, as defined in the appended claims.

I claim:

1. In combination with a door or other member mounted to swing about a hinge pivot, a torsional spring coiled to surround the axis of said pivot, a stop bar extending exteriorly of said spring and adapted to swing about the axis of said pivot, means for normally holding said bar stationary, 10 projections connected with the respective ends of the spring and mounted to swing with such spring ends, about the axis of said pivot, said projections being adapted to engage said bar on opposite sides and also to 11 be engaged and swung by the said swinging member, and means for releasing said bar so that it may swing with the spring.

2. In combination with a door or other member mounted to swing about a pivot 110 axis, a torsional spring coiled around said axis, a stop member arranged exteriorly of the spring, means for holding said stop member stationary, and projections connected with the respective ends of the spring 120 and mounted to swing with such spring ends, about the pivot axis, said projections being adapted to engage said bar on opposite sides and also to be engaged and swung by said swinging member.

3. In combination with a door or other swinging member, a stationary axle forming a hinge pivot for said member, a stationary collar secured to said axle, a torsional spring coiled to surround said axle, two collars 130

mounted on said axle loosely, one of said loose collars being adjacent to said stationary collar, a stop bar connecting said loose collars and extending exteriorly of said 5 spring, a movable pin adapted to connect said stationary collar with the adjacent loose collar, means for moving said pin from its coupling position to a releasing position, and projections connected with the ends of 10 the spring and mounted to swing with such spring ends, about the pivot axis, said pro-

jections being adapted to engage said stop bar on opposite sides and also to be engaged and swung by said swinging member.

In testimony, that I claim the foregoing 15 as my invention, I have signed my name in presence of two subscribing witnesses.

EMIL BOMMER.
